ABSTRACT OF THE DISCLOSURE

In a machine for winding textile threads on a bobbin wherein a thread guide is given a reciprocating movement along the thread receiving bobbin through a rotating element coupled with the bobbin, there are provided two distinct mechanisms for driving the bobbin, these mechanisms being brought into play alternatively, one for driving the bobbin at constant angular speed, and the other for driving the bobbin at constant peripheral speed, through a friction drive roller adapted, to be applied against the periphery of the body formed by the bobbin and the thread wound thereon.

This invention relates to the handling of textile threads and more particularly to a machine for automatically winding such threads onto bobbins or spools.

Still more particularly, this invention concerns winding machines of the type comprising a thread guide driven by a rotating element, such as a cam, in such a way as to undergo an alternating movement along the length of the thread-receiving bobbin, the spindles upon which said bobbin and said cam are respectively mounted being rotatably coupled in such a way that the rotation of one of them assures the rotation of the other.

It should be understood that, in accordance with standard usage in the textile industry, the word "bobbin" used hereafter may refer to the support element taken alone or to the combination of this support with the mass of thread wound thereon.

The machine of the present invention is characterised in that it comprises two distinct bobbin driving mechanisms permitting the bobbin to be selectively driven either at a constant radial velocity, by means of one of the above mentioned mechanisms coupled to the bobbin spindle, or at a constant peripheral, or tangential, velocity, by means of the other mechanism which comprises a friction drive roller capable of being applied against the periphery of the bobbin.

According to the preferred embodiment of this invention, the bobbin drive roller rotates in a support which can pivot about a rotatable shaft to which the roller is coupled through the intermediary of a belt, the pivoting of said support in one direction or the other about said shaft permitting the roller either to be applied against the periphery of the bobbin or to be moved away therefrom.

In addition, the thread guide may advantageously be mounted in another support which, at one end, can pivot about the axis of the guide cam and, at the other end, bears against the periphery of the bobbin through the intermediary of a bearing roller.

Said bearing roller and drive roller being preferably applied against the periphery of the bobbin along respective diametrically opposed generatrices of the cylinder defining said bobbin, the bobbin spindle is mounted in a cradle which is advantageously regulatable on the machine housing in such a way that the orientation of this spindle can be modified in a plane substantially parallel to a plane tangent to the two circular arcs described by the axes of rotation of the rollers during the

2

pivoting of their respective supports as the spool fills up, which modification permits the winding of a conical body of thread on a conical support.

In order to permit these conical bobbins to be wound under conditions assuring that both the thread guide support roller and the bobbin drive roller (which rollers could, if desired, be replaced by conical rollers) make as linear a contact as possible with the bobbin periphery, it is desirable to mount the drive roller on its pivotable support through the intermediary of a second cradle which is adjustably mounted on said support, in such a way that the orientation of the axis of rotation of this roller can be modified, with respect to the bobbin rotation axis in a plane tangent to the circular arc described by the roller axis when its support pivots.

These and other characteristics, features and advantages of the present invention will become more readily apparent from the following detailed description when taken together with the attached drawings, in which:

20 FIG. 1 is a side view, which is partially exploded and partially in cross-section, of a thread spooling machine using devices according to the present invention;

FIG. 2 is a view taken along the plane II—II of FIG. 1;

FIGS. 3 and 4 show two different points in the operating cycle of a unit forming a part of the apparatus shown in FIG. 2;

FIG. 5 is a partial side view showing a unit of the apparatus of FIG. 1;

FIG. 6 is a cross-sectional view taken along the plane 30 VI—VI of FIG. 5;

FIG. 7 is a side view of the drive mechanism of one of the units of FIG. 1, looking through the machine housing wall upon which the mechanism is mounted;

FIG. 8 is a cross-sectional view taken along the plane 35 VIII—VIII of FIG. 1;

FIG. 9 is a cross-sectional view of an alternative form of bobbin driving mechanism; and

FIG. 10 is a side view of the mechanism of FIG. 9, looking through the machine housing wall on which it is 40 mounted.

It should be understood that the right side of FIG. 1 shows a complete assembly while the left hand side reproduces, in exploded form, several of the elements thereof.

Referring first generally to the apparatus shown in FIG. 1, it should be appreciated that for each thread to be spooled coming from a supply spool, a spindle, a bobbin, a skein, a coil of thread, a sleeve, or any analogous source, none of which are shown, the spooling apparatus comprises, as is well known per se, a thread guide 2 driven by a rotating element, such as cam 3, in such a way as to undergo an alternating movement along the length of the thread-receiving bobbin 4 on which the thread is wound in the form of superposed helices the turns of which overlap one another. The support spindle, 5 or shaft, 5 of cam 3 and the support spindle, or shaft, 6 of bobbin 4 are rotatably coupled in such a way that the rotation of one assures the rotation of the other.

In accordance with one important feature of the present invention there are provided, for the driving of bobbin 4, two distinct mechanisms, both driven by transmission shaft 7, one of which mechanisms, when it is coupled to spindle 6, causes the bobbin 4 to rotate at a constant angular velocity (the peripheral velocity thus increasing as the addition of thread causes the bobbin diameter to increase), while the other mechanism, which comprises a friction drive roller 8, causes the bobbin to rotate at a constant peripheral velocity when roller 8 bears against the bobbin periphery (the bobbin angular velocity thus decreasing as it fills up with thread).

70 Such an arrangement thus gives one the possibility of carrying out the spooling operation with the bobbin 4 having a constant angular velocity, in which case the

rate at which thread is added to the bobbin increases in proportion to the increase in bobbin diameter, or to cause the thread to be delivered to the bobbin at a constant rate when the bobbin turns at a constant peripheral velocity.

Such an arrangement is desirable since the constantly advancing development of synthetic fibers, whose structures are continually made to differ more and more radically from the structure of natural fibers, the quality standards set for these new fibers and the different thread supply arrangements (twisting bobbins, spindles, coils, skeins, etc.) render it imperative that the thread be supplied at a constant rate, i.e., at a constant linear speed, in the production of bobbins having crossed threads, which bobbins must be wound precisely when, for example, intended for use in commercial knitting machines.

In the embodiment shown, the roller 8 is mounted on a support 9, the support having the general form of a housing which is free to pivot about shaft 7 towards shaft 4 under the effect of a spring or a counterweight (neither of which is shown). To shaft 7 are attached paired pulleys 10. One of these pulleys drives roller 8 by means of a belt 11. The other of these pulleys drives, through the intermediary of belt 12, one of the paired pulleys 13 fixed on the shaft of one of two drums 14 of a thread delivery capstan, the other one of the paired pulleys 13 driving the other drum 14 (not visible) of the capstan by means of a belt 15. The drums 14 of the driving capstan, which the thread 1 passes around and which are arranged between the supply bobbin (not shown) and the receiving bobbin 4, assure the advance of the thread prior to its arrival at thread guide 2.

When it is desired to cause spindles 5 and 6 to both rotate at a constant angular speed, thread 1 is freed from drums 14, the belts 11 and 12 are removed, and roller 8 is moved away from bobbin 4 by causing housing 9 to pivot in a counterclockwise direction about shaft 7 and by then bolting or otherwise blocking housing 9 by any appropriate means (not shown) in this retracted position.

In order to cause the shaft 7 to drive spindle 5 and, through the intermediary of spindle 5, also drive the spindle 6, pinions 16 and 17 (FIG. 7) are fixed on shaft 7 and spindle 5, respectively, these two pinions being mounted in the same plane and at a predetermined distance apart so as to be able to engage an intermediate pinion 18. This latter pinion is mounted for free rotation on an arm 19 which is in turn mounted to pivot about a pin 20 rigidly fastened to the machine housing 21. With this arrangement, it is possible to move pinion 18 away from pinions 16 and 17 when it is desired to decouple the latter two pinions so that bobbin 4 may be driven by roller 8, for which operation it is necessary to remount belt 11 between the roller and pulley 10.

In the above description it was assumed that the bobbin 4 was cylindrical. However, it often happens that it would be desirable to wind thread 1 onto a conical bobbin.

In order to permit such modified operation, roller 8 is mounted in a cradle 22 capable of pivoting on housing 9 about an axis perpendicular to the axis of shaft 7, this pivoting taking place, for example, about the longitudinal axis of fastening bolt 23 in such a way that the angular position of the axis of rotation of roller 8 can be changed while always maintaining it in a plane tangent to the circle C_1 which this axis describes about the axis of shaft 7 when housing 9 pivots around the shaft. Thus, regardless of the value of the apical angle of the cone defining the surface of bobbin 4 against which roller 8 must bear, cradle 22 may be so oriented that the axis of roller 8 will be parallel to the frusto-conical mass formed by the thread 1 wound on the bobbin with the result that roller 8 will bear evenly against the thread along the entire length of the bobbin.

In place of cylindrical roller 8, one could employ a

conical roller having the same apical angle as the cone defining bobbin 4.

In certain cases, particularly when it might be desired to wind threads of various thicknesses, it is advantageous to be able to alter the angular speed ratio existing between spindles 5 and 6.

For this purpose the present invention includes a mechanism through which spindles 5 and 6 are rotatively coupled, this mechanism being shown in FIG. 7 to comprise a pinion 24 mounted for rotation with a pulley 25 which is rotatively coupled to spindle 6 through a belt 26. The elements 24 and 25 are mounted so as to rotate freely about a pivot 27 supported in lever 28. This lever can pivot and slide, with respect to machine housing 21, because it is supported by a bolt 30 attached to the housing 21 and passing through an elongated slot 29 cut in one end of the lever. Thus pinion 24 can be displaced, while remaining in the plane of pinion 17, and can be positioned in such a way as to tighten belt 26 and to engage pinion 17, bolt 30 then being tightened to fix pinion 24 in this position.

This arrangement thus permits the distances between axis 27 and the axes of spindles 5 and 6 to be varied at will so that a rotating group (comprising a pulley and a pinion) having any desired diameters may replace the elements 24 and 25 in order to create any desired coupling ratio between spindles 5 and 6, i.e. the ratio between the frequency of oscillation of the thread guide and the rotation frequency of the bobbin 4.

In order to avoid any slippage between spindles 5 and 6, a toothed belt 26 is used in combination with toothed pulleys mounted on axes 6 and 27.

Because of the use of a flexible belt 26 to drive spindle 6 it is possible to employ another concept of the present invention according to which the bearings of spindle 6 are mounted in a support, such as the cradle 31 of FIG. 2, whose position on a projection 21a of housing 21 may be varied through a pivoting action about pivot 32, this pivoting taking place about a perpendicular axis.

The base of cradle 31 has at least one arcuate slot formed therein and having its radius of curvature centered on pivot 32, each said slot serving for the passage of a respective locking bolt 33 which screws into projection 21a to lock cradle 31 in position after it has been oriented in the position required to permit the axis of spindle 5 to be properly positioned with respect to the bobbin 4 when it is desired to employ a bobbin having a conical surface.

It is thus possible, under any given conditions, to regulate the angular position of cradle 31 in such a way that a bearing roller 45, which may be cylindrical or conic and whose axis can pivot about spindle 5 while remaining parallel thereto, bears on the bobbin 4 along its entire length, regardless of the apical angle of the bobbin's conical surface.

This regulation also permits the oscillating movement of thread guide 2, which movement is parallel to spindle 5, to be parallel to the generatrix of the conical surface of bobbin 4, regardless of the inclination of this generatrix.

Returning now to FIG. 1, there is shown a particularly useful form of construction wherein rollers 8 and 45 bear against respective diametrically opposed points on the circumference of bobbin 4, and the plane in which the axis of spindle 6 pivots about pivot 32 is parallel to the plane P-P₁ which is tangent to both of the circular arcs C_1 and C_2 describing, respectively, the pivoting of the axis of roller 8 about shaft 7 and the pivoting of the axis of roller 45 about spindle 5, these pivoting actions being effectuated by the pivoting of supports 9 and 44, respectively, in proportion to the filling up of bobbin 4.

It is thus possible to permit the thread to be wound on the bobbin in any conical manner while assuring that both rollers 8 and 45 maintain a perfectly linear contact with the conical body of wound thread.

Referring now to the means for moving the thread guide in the embodiment shown herein, these means com-

prise a rotating cam 3 mounted on spindle 5 (see particularly FIG. 2) and presenting a groove 34 in which slides a shoe 35 suspended from a slider 36 which slides parallel to the axis of spindle 5 along a slide formed by two shanks 37 arranged parallel to spindle 5.

Pivotedly mounted on a pivot 38 of slider 36 is a bell-crank lever 39 having its longitudinal axis generally perpendicular to shanks 37. Lever 39 carries, at one end, the thread guide 2 and, at the other end, a shoe 41 carried by a pivot 40 whose axis is parallel to the axis of pivot 38. The shoe 41 slides in a slideway 42, of the type generally referred to as a sine bar or pineapple bar, which can be angularly adjusted, in a plane parallel to the plane containing shanks 37, by means of a pivoting movement about a pivot 43 whose axis is parallel to those of pivots 38 and 40.

It may be appreciated that when cam 3 turns with spindle 5, shoe 35 drives slider 36 along shanks 37 in a back and forth movement which, as long as bar 42 is maintained parallel to shank 37, transmits an identical motion to thread guide 2 (as shown in FIG. 3), the path followed by thread guide 2 having precisely the same length as that followed by shoe 35.

If, on the other hand, the angular position of bar 42 with respect to shanks 37 were to be changed by causing the bar to pivot around pivot 43, in a counterclockwise direction for example (as shown in FIG. 4), lever 39 would pivot progressively during its travel in such a way as to give guide 2 a path of travel which is shorter than that of pivot 38. In other words, lever 39 pivots in a direction so that its end which carries guide 2 points toward the center of the bobbin and so that its angle of inclination increases in proportion to the distance separating shoe 41 from pivot 43 as slider 36 travels along shanks 37, so that the length of the path travelled by guide 2 decreases in proportion to the degree of rotation given bar 42.

This arrangement permits the winding of a bobbin so that its thread body has conical ends or ends having a curved cross-section by merely causing bar 42 to pivot gradually and continually in a counterclockwise direction at a constant or variable rate, depending on the contour desired.

According to the concept of the present invention, rotating cam 3, shanks 37 and bar 42 are all mounted in a support having the form of a housing 44 (FIGS. 1 and 2) capable of freely pivoting about spindle 5 and of bearing, through the intermediary of freely rotatable roller 45, against the periphery of bobbin 4, with the result that housing 44 pivots about spindle 5 by an amount which is proportional to the increase in the diameter of the body of wound thread. This pivoting of housing 44 is utilized to control the orientation of bar 42. More specifically, the gradual rotation of housing 44 is utilized to cause bar 42 to be gradually and continually pivoted by means, for example, of a cam 46 taking the form of a slideway rigidly mounted on machine housing 21.

In the embodiment shown in FIGS. 1-5, the cam 46 controls the position of bar 42 by guiding a finger 47 forming an extension of the bar. The configuration of the cam slot is such as to give the ends of the thread body a concave generatrix. If cam 46 were straight, the resulting ends would be conic and if the slot were in the form of a circular arc centered on the axis of spindle 5, the ends would be perpendicular to the axis of rotation of spindle 6.

In order to permit the form which the wound thread body is to take to be rapidly and easily selected, the cam 46 is advantageously mounted on a support plate 48 (FIGS. 5 and 6) by means of a locking bolt 49 which functions as a pivot to permit the orientation of the cam.

In the embodiment shown, five different predetermined inclinations may be given to the cam through the co-operation of a pin 51 on cam 46 with a respective one of five reference indentations 50 arranged in plate 48, the

engagement of pin 51 in each indentation permitting the ends of the thread body to have a different slope.

In addition, cam 46 is rendered detachable from plate 48 in order to permit the use of other cam configurations.

Instead of attaching plate 48 directly to machine housing 21, it is preferable to mount it on a support plate 52 which is made to oscillate with respect to housing 21 about an axis 53 at a frequency which is both low and aperiodic with respect to the frequency of rotation of bobbin 4.

This oscillatory movement is produced by an eccentric cam 54 (FIG. 1) which may be driven by the motor which drives bobbin 4 or by a separate motor 55. The rotation of cam 54 is translated, by a roller follower, into an oscillatory longitudinal movement of rod 56 which generates a pivotal motion in plate 52.

Plate 48 is advantageously mounted on support plate 52 through the intermediary of a pivot 57 and is fixed at an adjustable angular position with respect to plate 52 by means of a locking screw 57a.

The oscillatory movement of cam 46 with respect to axis 53 produces a certain variation in the length of the path traversed by guide 2. This variation serves to prevent the formation of hard projections along the edge of the thread body and to prevent the appearance of uneven zones on the bobbin where overlappings of the thread turns are concentrated, which zones would hamper the ability of the bobbin to empty rapidly as is required for industrial knitting machines.

This oscillatory movement permits the utilization, between thread guide 2 and cam 46, of a single coupling mechanism to assure, on the one hand, that the ends of the wound thread body have the desired form and, on the other hand, that the thread be regularly distributed around the bobbin.

The winding machine may comprise a large number of bobbins capable of being wound simultaneously, it being envisioned for example that twenty-four bobbins could be mounted, with twelve being mounted on each side of the machine housing wall 21. This wall is traversed longitudinally by a horizontal motor shaft 58 (FIG. 8) driven by a motor (not shown).

Between shaft 58 and each of the transmission shafts 7 (one shaft for each bobbin) there is disposed a clutch unit comprising a disc 59 mounted on shaft 58 and a plate 60 mounted on shaft 7 so as to rotate therewith but so as to be slidable axially thereon. A spring 61 constantly urges the plate 60 against the periphery of disc 59 with the result that the plate is continually driven in rotation by its friction contact with the disc as long as no counter pressure is exerted by clutch disengaging abutment 62. This abutment is moved by means of a control arrangement comprising a bent lever 63 pivoting about a pivot 64 mounted on a projection of housing wall 21.

According to a feature of this invention, the free end of lever 63 is acted on, on the one hand, by spring 65 which, by itself exerts a large enough force to counteract the effect of spring 61 and to assure the permanent disengagement of plate 60 from disc 59, and, on the other hand, by a control unit, such as lever 66, mounted so as to remove from abutment 62 the disengaging effect of spring 65, thereby assuring the engagement of the two members. Lever 66 is held in place in a clutch-engaging position by a bolting mechanism upon which act the various monitoring units associated with the spooling operation, such as a bobbin thickness gauge, thread tension monitors, etc., these units acting to halt the spooling operation when required by cancelling the effectiveness of the bolting mechanism, thereby permitting spring 65 to act on lever 66 in such a way as to cause plate 60 to become disengaged from disc 59.

As is shown in FIGS. 1 and 8, the preferred embodiment of the control unit comprises the lever 66 pivoted at 67 on a projection of housing wall 21. One end of the lever is joined, by means of a connecting rod 68, to the

free end of lever 63. Towards its other end, the lever 66 passes through a hole arranged in a slider 69 (see particularly FIG. 1) which is mounted against wall 21 in such a way as to be able to slide vertically with respect thereto when lever 66 is lowered by, for example, a downward pressure on knob 66a.

Slider 69 carries a finger 70 which can become latched behind a ramp 71 carried by a catch 72. The catch is adapted to pivot about an axis 73 mounted on housing wall 21 and is normally urged in a counterclockwise direction by a spring or counterweight (not shown).

The various monitoring units mentioned above are, in the preferred embodiment, made to act on this catch 72. These units produce, on the catch, a torque which tends to cause it to pivot in a clockwise direction around its axis 73. This has the effect of retracting the ramp 71 away from finger 70 and of permitting slider 69 and the portion of lever 66 which carries knob 66a to rise, thereby moving rod 68 downward so as to permit spring 65 to come into action and to cause shaft 7 to become disengaged from motor shaft 58.

Catch 72 may advantageously be made responsive to a bobbin thickness monitor so as to automatically halt the winding operation when the bobbin attains the desired diameter.

According to one useful form of construction, housing 44 is used as the thickness gauge, its angular position about spindle 5 being a function of the bobbin diameter as long as roller 45 contacts the bobbin.

To this end, there is mounted, on a wing 74 rigidly connected to housing 44, and lying in a plane perpendicular to the axis of spindle 5, a stop 75 (FIG. 1) positioned behind this wing and projecting towards machine housing wall 21 so as to intersect the plane in which catch 72 pivots.

The position of this stop 75 on wing 74 is desirably adjustable, such a capability being provided, for example, by the rotation of a screw 76 to place the stop 75 at any desired position relative to a scale 77 which could be graduated in millimeters to indicate the thickness of the thread layer to be wound on bobbin 4.

In operation, stop 75 is set opposite the scale graduation corresponding to the desired thread layer thickness and the winding operation is started. Housing 44 commences to pivot in a clockwise direction as the thread layer grows. This continues until stop 75 contacts catch 72 and causes it to pivot clockwise and to thereby trigger the disengagement of the clutch means and the stopping of bobbin 4, the moment of contact of stop 75 corresponding to the attainment of the desired thread layer thickness on bobbin 4.

It is also desirable to provide a gauge in the form of an antenna 78 which will sense the rupture of thread 1. This antenna is mounted so as to pivot freely about a pivot 79 to which its lower end is connected and which is mounted on wall 21. The upper extremity of the antenna bears against the thread 1 at a point between drums 14 and return-roller 80, the bearing point preferably being immediately below said roller. The force with which antenna 78 bears against thread 1 may be very accurately regulated by the adjustable counterweight 81.

If thread 1 were to break, the antenna 78 would lose its support point and, under the influence of gravity and then under the added influence of counterweight 81, would pivot in a clockwise direction around its pivot 79 until encountering wheel 82 provided at the upper end of catch 72. This would cause the catch to pivot and release slider 69, thereby triggering the disengagement of 7 from shaft 58.

When thread to be spooled is delivered from skeins or sleeves, it is particularly difficult to obtain good quality, precision wound bobbins whose turns overlap one another. In effect, if the skein or sleeve is poorly placed on its rotating support, called a drumhead, or if, as a result of careless maintenance, the rotating support becomes

entangled, the thread will not flow smoothly and will therefore have a greater tendency to break. It will be readily appreciated that each rupture reduces the quality of the finished bobbin and disturbs the continuous advance of the winding operation, and, hence increases the cost of the operation.

Assuming that rotating support 83 (FIG. 8) turns freely about a horizontal axis 84 mounted above the winding apparatus and fixed to the machine housing wall 21, there 10 is mounted, preferably on the same axis 84, a compensating beam 85 one end of which carries a thread return roller 86 around which the thread 1a turns after having ascended prior to descending in order to pass around drums 14. The other end of beam 85 is connected, through 15 the intermediary of rod 87, to a perpendicular projection 88 of catch 72 (FIG. 1).

If, with this structure, thread 1a becomes tangled in its support 83, the tension to which the thread is subjected will increase, causing roller 86 to be drawn downward, 20 with the result that rod 87 moves upward. This movement has the result to causing catch 72 to pivot in a clockwise direction so as to trigger the disengagement of shaft 7 from shaft 58. With the winding operation thus stopped, the thread on support 83 can be disengaged 25 by hand, so that all danger of breakage is eliminated. After each such stoppage, and after the trouble has been corrected, the winding operation may be restarted simply by depressing knob 66a.

In certain cases, wherein the driving of bobbin 4 at a 30 constant peripheral speed can not be satisfactorily produced by roller 8 alone this action may be aided by axially driving the bobbin, this axial driving being accompanied by a certain amount of slippage which serves to preserve the constant peripheral speed of the bobbin.

35 This driving with slippage may be obtained, in accordance with the present invention, by introducing a friction torque limiter into the bobbin axial driving mechanism. This torque limiter could, for example, replace the pinion 18 of the arrangement shown in FIG. 7. One form of such limiter is shown in FIGS. 9 and 10 to comprise a pair of pinions 18a and 18b rotatable independently of one another on the same pivot 89. A washer 90 is mounted so as to rotate with pinion 18a and to slide axially on surfaces parallel to pivot 89. This washer is urged by springs 29 against the bottom of pinion 18b. With pinion 18a 40 positively engaging driving pinion 16, which is mounted for rotation with shaft 7, and pinion 18b positively engaging pinion 17 of spindle 5, the friction existing between pinions 18a and 18b is determined in such a way that the velocity difference existing between that created by the axial bobbin drive and the peripheral bobbin drive is absorbed by slippage between these two pinions, i.e. 45 in such a way that the linear velocity of the thread delivered to the bobbin is maintained constant.

50 When it is desired to drive bobbin 4 only through its spindle 6, while completely removing the peripheral drive action of roller 8, it is only necessary to replace pinions 18a and 18b by a single pinion 18. It is preferable that these pinions 18a and 18b be removable as a unit with the pinions, their shaft 89, their mounting arm 19 and their shaft 20, by which they are attached to housing wall 21, all being held in place by an easily removable nut 93.

55 Also, instead of making pinions 18a and 18b removable, they may be permanently mounted and provided 60 with any well-known blocking means which cause the two pinions to rotate in unison.

70 While one particular embodiment of the present invention has been shown and described herein, it should be appreciated that many variations and modifications would occur to one skilled in the art without departing from the spirit of the invention, whose coverage should therefore be limited only by the scope of the appended claims.

75 What I claim is:

1. In a machine for winding textile threads onto a bobbin, which machine comprises a thread guide, a rotat-

ing element driving said thread guide in an alternating movement in the direction of the longitudinal axis of a bobbin, a first spindle upon which said rotating element is mounted, a second spindle for receiving a bobbin, said spindles being coupled in such a way that the rotation of one of said spindles assures the rotation of the other, and driving means for actuating said bobbin, the improvement which consists in that said driving means comprise a first mechanism for driving said bobbin at a constant angular velocity, a second mechanism for driving the body formed by said bobbin and the thread wound thereon at a constant peripheral velocity, said second mechanism including a friction drive roller, and coupling means for alternately connecting said first mechanism to one of said spindles or applying said roller against the periphery of said body.

2. A device as recited in claim 1, further comprising: a support in which said thread guide is mounted, said support being mounted, at one end thereof, so as to be pivotable about the axis of said first spindle, and a bearing roller mounted in the other end of said support so as to turn freely and so as to bear against the periphery of the said body.

3. A device as recited in claim 1, further comprising: a power transmission shaft, a support in which said roller is rotatively held and which is mounted so as to pivot about said power transmission shaft, and a drive belt rotatively coupling said power transmission shaft to said roller, whereby the pivoting of said support in one direction permits said roller to be applied against said body and its pivoting in the other direction causes said roller to be moved away from said body.

4. A device as recited in claim 3, further comprising a second support in which said thread guide is mounted, said second support being mounted, at one end thereof,

so as to be pivotable about the axis of said first spindle; and a bearing roller mounted in the other end of said second support so as to turn freely and so as to bear against the periphery of said body.

5. A device as recited in claim 4 wherein said drive roller and said bearing roller are positioned so that, when they contact said body, each roller bears against a respective diametrically opposed generatrix of the surface of revolution defining said body.

10 6. A device as recited in claim 5 further comprising a first cradle in which said second spindle is rotatively mounted, said cradle being movable in such a way that the orientation of the axis of said second spindle can be modified while remaining in a plane substantially parallel

15 to the common tangent plane of the two circular arcs described by the movement of the axis of rotation of said two rollers as their respective supports pivot, which modification of said second spindle permits the winding of a frusto-conical body of thread on a frusto-conical support.

20 7. A device as recited in claim 6, further comprising a second cradle in which said drive roller is rotatably mounted, said second cradle being movable in such a way as to modify the orientation of the axis of rotation of said 25 drive roller while maintaining said last named axis in a plane tangent to the circular arc described by this axis when its support pivots about said power transmission shaft.
